Farnum F. Dorsey

UNITED STATES PATENT OFFICE.

FARNUM F. DORSEY, OF WINCHESTER, MASSACHUSETTS.

SAFETY-RAZOR.

1,239,577.

Specification of Letters Patent. Patented Sept. 11, 1917.

Application filed August 7, 1916. Serial No. 113,442.

To all whom it may concern:

Be it known that I, FARNUM F. DORSEY, a citizen of the United States, residing at Winchester, in the county of Middlesex and 5 Commonwealth of Massachusetts, have invented certain new and useful Improvements in Safety-Razors; and I do hereby declare the following to be a full, clear, and exact description of the invention, such as 10 will enable others skilled in the art to which it appertains to make and use the same.

This invention relates to razors of the type in which the blade, when in shaving position, is held with its length transverse 15 to that of the handle or stock on which it is mounted. More particularly, the invention relates to razors, of the said type, in which provision is made for cleaning and stropping the blade without removing it 20 from the stock, by connecting the blade pivotally with the stock so that it may swing, from its normal shaving position, into a position in which it may be stropped, and vice-versa.

25 One object of the present invention is to produce a razor in which the blade, both when used in shaving position and when stropped, shall have that position, relative to the handle by which the razor is manipulated, which experience has demonstrated to be most convenient and effective. It has been found that under both of said conditions it is desirable that the edge of the 30 blade be located or offset, from the axis of the handle, only a comparatively short distance, which is substantially less than the width of most commercial blades as now manufactured for safety-razors. Where the distance in question is too great the razor 35 tends to turn in the hand when used for shaving, while in stropping it is difficult to produce and regulate the proper degree of pressure of the edge against the strop.

To attain this object of the invention it is 40 proposed to mount the blade upon a stock having a lower handle-portion, by which it is manipulated, and a rearwardly offset upper portion or arm to the upper end of which the blade is pivotally connected. By 45 this offset arrangement the edge of the blade may be brought back to the proper position relative to the axis of the handle.

In previous razors of the kind in question it has been proposed to mount the blade 50 pivotally upon a stem which is arranged to slide telescopically within the handle, for

the purpose of removing the blade from the guard and engaging it with a retaining-device. Such construction involves a certain degree of weakness, and the liability to 60 looseness or play between the handle and the blade, which is especially apparent when the parts are in the extended stropping position. A second object of the present invention is to provide for the more secure support of the blade at all times, and more 65 particularly in the stropping position, and this object is attained by mounting the blade upon a rigid and unitary member or stock. This arrangement involves the use 70 of a guard and a blade-retaining device which are movable upon the stock to bring them into and out of coöperative relation with the blade, and as a convenient means for securing such movement the handle is 75 formed as a sleeve or outer telescopic member, while a stem, which is slidably or telescopically arranged within the handle, carries the guard and the retaining-device.

When the razor is used for shaving a 80 comparatively short stock is sufficient, while for stropping the razor a longer stock is desirable. An object of the present invention is to produce a razor, of the kind in question, in which the stock shall be of sufficient 85 length for convenient stropping, while being of less effective length when the razor is in shaving position—in which position it is desirable that it be as short and compact as possible for convenience in packing 90 and transporting the razor.

To the end last mentioned the inner sliding stem of the present razor is arranged to pass entirely through the handle, but to terminate at or near the lower end of the 95 handle when the parts are in the shaving position. When the parts are placed in the stropping position the stem is moved to a lower position in the handle, and this results incidentally in projecting the stem below the handle so as to increase the effective length of the stock as a whole.

Other objects of the invention, and the features of construction by which they are attained, will be set forth hereinafter, in 105 connection with the description of the illustrated embodiment of the invention.

In the accompanying drawings Figure 1 is a side-elevation of a razor embodying the present invention, with the parts in the 110 shaving position; Fig. 2 is a vertical median sectional view of the razor, with the

parts in the same position as in Fig. 1; and Figs. 3, 4, and 5 are, respectively, a plan-view, a side-elevation and a front-elevation, showing the razor with its parts in position 5 for stropping or cleaning.

The invention is illustrated as embodied in a safety-razor adapted for use with blades of a well-known form, but it will be apparent that blades of other forms may be 10 readily substituted by slight changes which need not be described. The blade, as shown, comprises a body 10 of thin sheet-steel, which is provided with a thickened back 11, made by bending and clamping a strip of 15 sheet-metal around the edge of the body 10.

The blade is held, removably, in a blade-holder 12. This blade-holder consists of a piece of sheet-metal bent into U-shape, in cross-section, and it embraces the back 11 of 20 the blade closely, and with a spring-action sufficient to prevent accidental longitudinal displacement. The blade is introduced and removed longitudinally, and lateral movement of the blade in the holder is prevented 25 by in-turned lips 13 at the edges of the holder, these lips embracing the shoulders formed by the back 11 of the blade.

A guard coöperates with the blade, this guard comprising the usual teeth 14, which 30 are formed at the edge of a plate 15. The guard-plate is also provided with hooks 16 and lugs 17 which embrace the blade at the extremities of its cutting-edge and assist in maintaining the proper relative operative 35 position of the blade and the guard.

The blade-holder and the blade are supported and manipulated by means of a stock which comprises two parts. The part 18 is suitably formed to be securely grasped 40 and turned in the hand in the operations of shaving and stropping, and is, accordingly referred to hereinafter as the "handle." The other part 19 is in the form of an extension or arm, which extends parallel with 45 the axis of the handle but is offset therefrom, rearwardly, a substantial distance, for a purpose which has already been set forth.

The blade-holder 11 is connected, at the middle of its length, with the arm 19 by a 50 swivel-joint which permits angular or turning movements of the holder both about an axis parallel with its length, and about an axis transverse to its length. For this purpose a swivel-stud 20 is arranged to turn 55 in a hole in the upper end of the arm 19, and this stud is provided with a head 21 which is bored transversely to receive a pivot-pin 22. The pin is soldered or otherwise secured to the back of the blade-holder, 60 which latter is also recessed to clear the head 21.

The guard is supported by a stem which slides within a bore extending through the handle. This stem comprises an upper part 65 23 of greater diameter, and a lower part 24

of less diameter, the part 24 extending beyond the lower end of the handle and terminating in an enlarged end or knob 26.

A compression-spring 25, coiled around the part 24 of the stem, acts, at its upper 70 end, against a shoulder on the stem and tends to force the stem upwardly. Accordingly, when the parts are in shaving position the guard is constantly pressed upwardly, this movement being arrested by the 75 blade, through its engagement with the hooks 16.

The arrangement just described compensates automatically for variations in the widths of the blades which may be used, 80 and provides for a close and firm fitting of the parts under all conditions.

To prevent the guard-plate from turning, about the axis of the stem, the plate is provided with two ears which embrace the arm 85 19 laterally, as shown in the drawings.

When the blade-holder and the blade are in the stropping position, as shown in Figs. 3, 4, and 5, it is necessary to retain them securely against rocking movements in any 90 direction, and for this purpose a retaining-device is employed which also is mounted on the stem. This device is in the form of a narrow block 27, which is provided with a narrower upwardly-projecting tongue 28. 95 This tongue is adapted to enter either end of the blade-holder 12 and to be closely embraced thereby, and in order to provide space in the blade-holder for this purpose the blade-holder is made long enough to extend 100 slightly beyond the blade at each end, and the lips 13 are also interrupted at the ends of the blade-holder.

For convenience in manipulating the razor the rear corners of the guard-plate 15 are 105 curved downwardly. When the parts are to be moved from shaving position to stropping position these corners are pressed downwardly, thus depressing the guard and the stem. The blade is then swung into 110 stropping position and the guard and stem are allowed to rise sufficiently to engage the retaining-device with the blade-holder. The spring then acts to retain the parts in the stropping position.

In previous razors of the type in question the blade has been mounted on the inner telescopic member, or stem, while the guard has been mounted on the outer member, or handle. By the reversal of this arrangement 120 several important advantages are secured in the present razor. In the first place, this novel arrangement renders it possible to offset the point of pivotal attachment of the blade rearwardly, with the advantages before set forth. In the second place, the connections between the handle and the blade are rendered more rigid, by the exclusion of the sliding joint between the handle and the stem, and this is a valuable feature in stro- 125 130

ping the razor. In the third place, the manipulation of the razor in changing it from shaving position to stropping position, and vice-versa, is facilitated, since it is necessary 5 only to press down the guard-plate with two fingers, as hereinbefore described, to release the blade, which may then be conveniently turned from one position to the other without the necessity of sustaining the spring- 10 tension by prilling at the same time on the blade, as would be necessary were the blade mounted on the stem in the usual manner.

When the parts are in shaving position the end-knob 26 of the stem is close to the end 15 of the handle, but when the stem is depressed to the stropping position it projects beyond the handle, thus substantially increasing the effective length of the stock and facilitating the stropping operation.

20 An incidental advantage of the present construction resides in the fact that the blade can at any time, without removal from the holder, be turned over to bring its other face to the outward position, and it has been 25 found that such reversal increases the useful duration of the edge between successive stropping operations.

My invention is not limited to the embodiment thereof hereinbefore described, and 30 illustrated in the accompanying drawings, but it may be embodied in various other forms within the nature of the invention as it is defined in the following claims.

I claim:

35 1. A razor having, in combination, a stock including a grasping-portion or handle, and an upper portion rigidly connected with the handle; a blade; pivotal connections, directly between the blade and said upper portion of the stock, upon which the blade may be turned about an axis transverse to its length; a guard; and movable connections, between the guard and the stock, upon which the guard may move toward and from the 45 blade, from an upper shaving position to a lower stropping position.

2. A razor having, in combination, a stock including a grasping-portion or handle, and an upper portion rigidly connected with the 50 handle; a blade; pivotal connections, directly between the blade and said upper portion of the stock, upon which the blade may be turned about an axis transverse to its length; a guard; movable connections, between the guard and the stock, upon which the guard may move, toward and from the blade, from an upper, shaving position to a lower stropping position; and a spring tending 55 to move the guard toward the blade.

60 3. A razor having, in combination, a stock including a grasping portion or handle, and an upper portion rigidly connected with the handle; a blade; pivotal connections, directly between the blade and said upper portion of the stock, upon which the blade may

be turned about an axis transverse to its length; a guard; sliding connections, between the guard and the stock, upon which the guard may move, toward and from the blade, in a direction longitudinal with respect to the stock; and means for normally retaining the guard against such movement when in engagement with the blade. 70

4. A razor having, in combination, a stock including a grasping-portion or handle, and 75 an upper portion rigidly connected with the handle; a blade; pivotal connections, directly between the blade and said upper portion of the stock, upon which the blade may be turned about an axis transverse to its 80 length; a guard; movable connections, between the guard and the stock, upon which the guard may move toward and from the blade; and means, connected to and movable with the guard, for retaining the blade 85 against movement about its said pivotal connections when it is in stropping position, parallel with the stock.

5. A razor having, in combination, a hollow handle; an arm extending upwardly, 90 but rearwardly offset, from the handle; a blade-holder pivoted, at the middle of its length, to the upper end of said arm so as to swing about an axis transverse to the length of the blade-holder; a stem 95 slidable in the handle; means carried by the stem, for engaging and holding an end of the blade-holder when it is in stropping position; and a guard movable toward and from the blade-holder and connected to operate 100 with said stem.

6. A razor having, in combination, a hollow handle; a blade-holder connected, at the middle of its length, with the handle through a joint adapted to permit the blade-holder to swing about a longitudinal axis and also about a transverse axis; a stem 105 slidably mounted in the handle; a guard carried by the stem; and a retaining-device also carried by the stem and adapted to engage the end of the blade-holder and retain it against swinging movement. 110

7. A razor having, in combination, a stock; a blade; a blade-holder in the form of a clip with open ends, the blade-holder being longer than the blade so as to extend, beyond the ends thereof; connections, between the blade-holder and the stock, adapted to permit the blade-holder to swing about a longitudinal axis and also about a transverse axis at the middle of its length; and a retaining device adapted to enter the end 120 of the blade-holder and to prevent swinging movement thereof about either of said axes. 125

8. A razor having, in combination, a hollow handle; an arm extending upwardly, but rearwardly offset, from the handle; a blade-holder pivoted, at the middle of its length, to the upper end of said arm so as to swing about an axis transverse to the 130

length of the blade-holder; a stem slidable in the handle; and a guard carried by said stem and movable therewith toward and from the blade-holder.

5. A razor having, in combination, a handle; an arm extending upwardly, but rearwardly offset, from the handle; a blade-holder pivoted, at the middle of its length, to the upper end of said arm so as to swing 10 about an axis transverse to the length of the blade-holder; and a guard connected with the handle and movable toward and from the blade-holder.

10. A razor having, in combination, a handle; an arm extending upwardly, but rearwardly offset, from the handle; a blade; means for pivotally connecting the blade, at a point adjacent the middle of its rear edge, to the upper end of said arm so as to swing 20 about an axis transverse to the length of the blade; and means, including a guard, movably connected with the handle and adapted to retain the blade in either shaving position, with its length transverse to said arm, 25 or stropping position, with its length substantially parallel with the arm.

11. A razor having, in combination, a handle; an arm extending upwardly, but rearwardly offset, from the handle; a blade; 30 means for pivotally connecting the blade, at a point adjacent the middle of its rear edge, to the upper end of said arm, so as to swing about an axis transverse to the length of the

blade; a guard connected with the handle so as to be movable alternatively into coöperative relation with the blade, when the latter is in shaving position, with its length transverse to said arm, and into a position below the lower end of the blade, when the blade is in stropping position with its length substantially parallel with said arm; and means connected with and movable by, the guard, for retaining the blade in stropping position.

12. A razor having, in combination, two 45 telescopically arranged members, of which the outer one constitutes a stock for the razor, and the inner one extends entirely through the outer one; a blade pivotally connected, at the middle of its length, with 50 the upper end of the stock; and a guard mounted on the upper end of the inner telescopic member.

13. A razor having, in combination, two 55 telescopically arranged members, of which the outer one constitutes a stock for the razor, and the inner one extends entirely through the outer one; a blade pivotally connected, at the middle of its length, with 60 the upper end of the stock; and means, on the upper end of the inner telescopic member, for retaining the blade in stropping position, with its length substantially parallel with the stock.

FARNUM F. DORSEY.
